[57] CLAIM

The ornamental design for a combined luggage flap, tab and concealed catch or similar article, as shown and described.

DESCRIPTION

FIG. 1 is a top plan view of a combined luggage flap, tab and concealed catch showing my new design;

FIG. 2 is a top plan view thereof with a portion of the pocket folded back to expose the latch assembly;

FIG. 3 is a bottom plan view of FIG. 1;

FIG. 4 is an exploded top plan view of FIG. 1;

FIG. 5 is a right side elevational view of FIG. 1; and FIG. 6 is a cross-sectional view taken along line 6—6 of FIG. 1.
